GRASS DRYING APPARATUS

John Ernest Newman, Cirencester, England, assignor of two-thirds to Donald Stuart Kennedy, Andover, England

Application December 11, 1944, Serial No. 567,677
In Great Britain November 22, 1943

5 Claims. (Cl. 34—206)

1

This invention relates to apparatus for drying grasses and the like by means of hot air or flue gases from a furnace or other source, and more particularly to improved apparatus of the kind described in my pending application Serial No. 516,607 filed January 1, 1944, now Patent Number 2,381,076, issued August 7, 1945.

The invention has for its main object to provide improved drying apparatus comprising a plurality of inclined guides for the ascent of the material being dried.

The invention has for another object to provide improved means for elevating the material along the guides, the several elevating means operating successively so as to give a more balanced load upon the driving motor.

Other objects and advantages of the invention will hereinafter appear from the following description of a preferred embodiment, given with reference to the accompanying drawings, in which:

Figs. 1 and 1a together represent a side elevation of the improved apparatus, as seen in section on the broken line A—B—C—D of Fig. 2.

Figs. 2 and 2a together represent an end elevation of the apparatus, as seen in section on the line E—F of Fig. 1a.

Figs. 3 and 4 are details showing the drive to the grass-elevating means, Fig. 3 being a plan view and Fig. 4 an elevation.

As illustrated in these drawings, the apparatus is housed in a sheet-metal casing 10 provided with an arched roof 11, the interior being divided longitudinally and approximately along the center line by a vertical wall 12 extending up to the same level as the side walls; another vertical wall 13, parallel to the first but of slightly less height and connected to it by a sloping cover 14, further divides the interior to provide two chambers of approximately equal width, the inner one 15 being closed at the top by the sloping cover 14 and the outer one 16 being open to the space beneath the arched roof. The half of the casing which includes these two chambers is closed at both ends by vertical walls 17.

The outer chamber 16 receives a supply of hot air from a furnace (not shown) located externally of the casing, by way of a flue 18 conveying the hot air through the outer wall 19 of the casing just below the edge of the roof; a rotary fan 20 of propeller type, mounted in a circular hole or tunnel 21 in the adjacent interior wall 13 and driven by a shaft 22 extending through the outer wall, forces this hot air in mixture with air drawn over the sloping cover 14 from the other half

2

of the casing, into the inner chamber 15 from which it is delivered beneath the inclined guides on which the grass is supported.

These inclined guides, which are provided with longitudinal slots as described in my pending application already mentioned, occupy compartments in the other half of the casing and may project at the two ends for the feed and discharge respectively. If two inclined guides are provided, as shown in Figs. 1 and 1a, the first one may include a horizontal feed portion or platform 23, projecting beyond the casing, an inclined portion 24 (set at an angle of 30 degrees to the horizontal, for example) and a horizontal transfer portion 25 extending from the upper end of the incline to connect with a shelf 26 running transversely between the center wall 12 and the other outside wall 27 of the casing; the second guide 28 will be wholly inclined (for example, at an angle of 20 degrees to the horizontal), its lower end being connected to the bottom of a vertical partition formed by a closure or check plate 29 extending down from the transverse shelf 26, and its upper end being connected to the top of a closure or dead plate 30 at the end of the casing, where a shelf or chute 31 for the discharge of the dried grass from the second guide may be fixed. An opening 32 of suitable depth above the shelf or chute 31 is defined by another dead plate or closure 33 which may be hinged at 34 so as to rest lightly upon the grass as it travels over the shelf or down the chute. The discharge chute 31 may be hinged so as to vary the angle of discharge.

The guides 23, 24, 25 and 28 may be formed by flat-section members, extending side by side with air slots 36 between them, as seen in Fig. 2, the ends of the individual members being connected to the shelves 26 and 31 by bolts 35, say 2 inches long, so that the grass has a fall from the guides to the shelves. This arrangement provides an air seal at the upper end of each inclined plane or guide, the seal being formed by a layer of grass of a thickness increased by the height of the bolts 35, but any grass which is partially drawn into the slots 36 can be freely discharged at the upper ends by the feeding movement of the elevating spikes.

The horizontal feed portion or platform 23 of the first inclined guide projects into a bin or trough 37 adjacent to the end of the casing, the wet grass being forked or otherwise supplied to this bin over a chute 38 inclined at an angle of 45 degrees for example; the grass is carried over the feed portion 23 by spikes 39 extending ver-

tically through slots in the platform and is then elevated along the inclined portion 24 by similar spikes 40 extending at right angles to said inclined portion and operating through the air slots 36 therein, until it reaches the top of the incline, from which it is carried over the horizontal transfer portion 25 by similar spikes 41 extending vertically through slots therein. The three sets of spikes 39, 40 and 41 are mounted upon parallel bars 42, for example horizontal angle-irons, supported upon a moving framework 43 of cranked shape, for example two angle-irons set on their corners in parallel vertical planes and each cranked to provide two horizontal lengths connected by an inclined length, in conformity with the shape of the guide. Two crank shafts 44 and 45, extending transversely of the first drying compartment 46 and below the inclined guide, carry the moving framework 43 upon cranks 47 and 49 set parallel to one another, so that the rotation of the crankshafts will cause the framework 43 to impart a circular orbital motion to the spikes, as described in my pending application mentioned above.

The second inclined guide 28 is also provided with a set of spikes for elevating the partly dried grass which falls upon its lower end after tumbling over the transverse shelf 26 from the transfer portion 25 of the first guide; these spikes 49 are likewise mounted upon parallel bars 50 supported upon a moving framework 51, the latter being straight and carried by cranks 52 and 53 of two other crankshafts 54 and 55 extending transversely of the second drying compartment 56 and having their cranks 52 and 53 set parallel to one another. These two crankshafts 54 and 55 are coupled together and to the first-mentioned crankshafts 44 and 45 by connecting rods engaging parallel cranks upon the extremities of the shafts, for example three cranks 57, 58 and 59 within the distribution chamber and two cranks 60 and 61 outside the casing; these cranks 57 to 61 inclusive will all be set parallel so that the four crankshafts 44, 45, 54 and 55 rotate in synchronism, but the internal cranks 47, 48, 52 and 53 carrying the respective frameworks 43 and 51 for the elevating spikes are preferably set oppositely in pairs, so that as one framework rises for its spikes to elevate the grass upon one inclined guide, the other framework will be falling with its spikes withdrawn from the grass, thereby giving a more even and balanced action.

The crankshafts 44, 45, 54 and 55 of the grass-elevating means may be driven by the same source of power as the fan 20, for example by an engine (not shown) coupled by a belt 62 to the pulley 63 on the fan shaft 22; a second pulley 64 on the latter is connected by a belt 65 to a variable-speed reducing mechanism 66 shown in Fig. 3, whereby the crankshaft 53 can be driven at a suitable low speed, for example up to about 6 revolutions per minute. The end of this crankshaft 55 projecting beyond the second drying compartment 56 is coupled by a connecting rod 67 to the adjacent end of the other crankshaft 54 in this same compartment; the opposite end of the crankshaft 54 is coupled by a connecting rod 68 to the crankshaft 44 at the lower end of the first inclined guide and by an obliquely arranged rod 69 to the crankshaft 45 near the upper end of that guide. All the driving cranks 57 to 61 inclusive connected by these rods are set parallel to one another, so that the shafts all rotate in unison, being coupled together in pairs

by the moving frameworks 43 and 51; however, as already stated, the internal cranks 47, 48, 52 and 53 carrying the respective frameworks are set oppositely in pairs, as shown in Figs. 1 and 1a.

5 The variable speed mechanism 66 is preferably of the type comprising a variable throw friction ratchet; as shown, a countershaft 70, rotated by a pulley 71 driven by the belt 65, carries a sliding cam or eccentric 72 of varying throw, adjustable 10 axially along the shaft by means of a striking fork 73, and the driven crankshaft 55 is fitted with a frictional wheel 74, the rim 75 of which is engaged by a friction ratchet lever 76 held down upon the cam 72 by a spring 77. As the 15 cam rotates, it lifts the lever 76, causing a shoe 78 fitted to its other end to grip the rim of the wheel 74, so that the latter is turned through a small angle at each upward stroke of the lever, the extent of the movement being variable by 20 shifting the cam 72 along the countershaft 70; on the return stroke of the lever, the countershaft remains stationary, being held by a friction pad or brake (not shown) engaging the wheel 74 or its shaft.

25 The larger part of the hot air delivered by the fan 20 to the distribution chamber 15 passes freely through an opening 79 in the center wall 12 to beneath the first inclined guide 24 and its upper transfer portion 25 in the first drying compartment 46; the remainder passes through a second and smaller opening 80 in the center wall 12 to beneath the second guide 28. The hot air which has traversed the wet material on the lower part of the first inclined guide 24, being highly charged with moisture, may be allowed to escape to the atmosphere, as described in my pending application Serial No. 516,607; for this purpose, the roof-space over the first drying compartment 46 is divided by a vertical partition 81 extending transversely of the casing 10, approximately over the middle of the length of the inclined portion 24 of the guide. The space between this partition and the closed end 11 of the casing, adjacent to the lower part of the first guide, is provided with a horizontal outlet pipe 82 of large cross-sectional area; an adjustable flap 83, hinged to the lower edge of the partition 81, hangs down towards the mass of grass travelling up the guide, so that by adjustment of the angle of the flap 83 a larger or smaller length of the guide is placed in communication with the outlet 82 for escape of highly moist air.

55 The hot air which has traversed the material on the upper part of the guide 24 and on the horizontal transfer portion 25 at its upper end, being less charged with moisture, is allowed to rise over the sloping cover 14 and descend into the air-mixing chamber 16, being drawn into the latter by the fan-suction for mixture with the hot gases from the furnace and recirculation through the drying compartments; this air current is shut off from the escape to atmosphere by the adjustable flap 83 and vertical partition 81.

60 65 The hot air which has passed beneath the second inclined guide 28 and traversed the partly dried material thereon, being only slightly charged with moisture, is also allowed to pass over the sloping cover 14 and descend into the air-mixing chamber 16 for recirculation.

70 75 The dried material discharged over the upper end of the second guide 28 may be cooled off by the entrance of cold air admitted laterally through the grass upon the shelf or chute 31, under the suction-effect exerted by the fan 20, this

air then mingling with the air from the second guide.

What I claim is:

1. Grass drying apparatus, comprising two inclined guides for upward sliding movement of masses of grass, said inclined guides being spaced horizontally from one another and arranged for movement of the grass up the two inclined guides successively, mechanical means for elevating grass along said inclined guides in series, the upper end of the first of said inclined guides being at a higher elevation than the lower end of the second of said inclined guides, said inclined guides including apertures, means for blowing a gaseous drying medium beneath said inclined guides for flow through said apertures therein and through the ascending grass thereon, guiding means extending from the upper end of the first of said inclined guides to the lower end of the second of said inclined guides, the grass from the upper end of said first inclined guide tumbling down over said guiding means onto the lower end of said second guide, and means for operating said mechanical elevating means, said operating means including driving cranks set in opposite phases for the respective inclined guides.

2. Grass drying apparatus comprising two inclined guides for upward sliding movement of masses of grass, said inclined guides being spaced horizontally from one another and arranged for movement of the grass up the two inclined guides successively, the upper end of the first of said inclined guides being at a higher elevation than the lower end of the second of said inclined guides, said inclined guides including apertures, means for blowing a gaseous drying medium beneath said inclined guides for flow through said apertures therein and through the ascending grass thereon, guiding means extending from the upper end of the first of said inclined guides to the lower end of the second of said inclined guides, the grass from the upper end of said first inclined guide tumbling down over said guiding means onto the lower end of said second guide, and mechanical means for elevating grass along said inclined guides in series, said mechanical means including two rigid frames extending adjacent to the respective inclined guides, spikes secured to said frames and adapted to extend through said apertures, a pair of crankshafts having parallel cranks for operating each of said frames, means for imparting rotary motion to said crankshafts, each of said frames including bearings upon the parallel cranks of one pair of said crankshafts, and the parallel cranks of one pair of said crankshafts being set in opposite phase to the parallel cranks of the other pair of said crankshafts.

3. Grass drying apparatus, comprising a roofed casing, a wall dividing said casing longitudinally into two parts, a parallel wall dividing one of said parts into two chambers, one of said chambers being open to the roof-space of said casing, a top cover connecting said walls above the other of said chambers, two inclined guides for upward sliding movement of masses of grass being arranged longitudinally in series in the other part of said casing, the upper end of the first of said inclined guides being at a higher elevation than the lower end of the second of said inclined guides, a transverse partition dividing said other part above the middle of the first inclined guide into two sections, the section above the lower end of said first guide having an outlet to the exterior, said guides including apertures, mechani-

cal means for elevating grass along said guides from the lower end of the first guide to the upper end of the second guide, guiding means extending from the upper end of the first guide to the lower end of the second guide, the grass from the upper end of said first guide tumbling down over said guiding means onto the lower end of said second guide, means for delivering a hot gaseous drying medium to said one chamber, means for blowing said medium from said one chamber to said other chamber, and passages for flow of said medium from said other chamber to beneath the respective guides for flow through the apertures therein and through the ascending grass thereon, and the medium flowing through the grass on said second guide passing over said other chamber into said one chamber for mixing with the medium to be blown into said other chamber, and the medium flowing through the grass on the lower part of said first guide escaping through said outlet.

4. Grass drying apparatus, comprising a casing including sides, ends and a roof, an internal wall dividing said casing longitudinally into two parts, a parallel internal wall dividing one of said parts into two chambers, one of said chambers and the other of said parts being open to the roof-space of said casing, a top cover connecting said internal walls above the other of said chambers, two inclined guides for upward sliding movement of masses of grass being arranged longitudinally in series in the other part of said casing, the upper end of the first of said inclined guides being at a higher elevation than the lower end of the second of said inclined guides, said guides including apertures, a transverse partition dividing the roof-space above the middle of the first inclined guide into two sections of unequal length, the shorter section above the lower end of said first guide having an outlet to the exterior, mechanical means for elevating grass along said inclined guides from the lower end of the first guide to the upper end of the second guide, guiding means extending from the upper end of the first guide to the lower end of the second guide, the grass from the upper end of said first guide tumbling down over said guiding means onto the lower end of said second guide, means for operating said mechanical elevating means, said operating means including driving cranks set in opposite phase relation for the respective guides, means for delivering a hot gaseous drying medium to said one chamber, means for blowing said medium from said one chamber to said other chamber, and passages for flow of said medium from said other chamber to beneath the respective guides for flow through the apertures therein and through the ascending grass thereon, the medium flowing through the grass on said second guide passing over said other chamber into said one chamber for mixing with the medium to be blown into said other chamber, and the medium flowing through the grass on the lower part of said first guide escaping through said outlet.

5. Grass drying apparatus, comprising a casing including sides, ends and a roof, an internal wall dividing said casing longitudinally into two parts, a parallel internal wall dividing one of said parts into two chambers, one of said chambers and the other of said parts being open to the roof-space of said casing, a top cover connecting said internal walls above the other of said chambers, two inclined guides for upward sliding movement of masses of grass being arranged in the other

part of said casing, said inclined guides being spaced horizontally from one another for movement of the grass up the two inclined guides successively, the upper end of the first of said inclined guides being at a higher elevation than the lower end of the second of said inclined guides, said guides including apertures, one of said inclined guides having its lower end adjacent to an inlet in one end of said casing, the other of said inclined guides having its upper end adjacent to a discharge opening in the other end of said casing, means for guiding the grass from the upper end of said first inclined guide to the lower end of said second inclined guide, a transverse partition dividing the roof-space above the middle of the first inclined guide into two sections, the section above the lower end of said first inclined guide having an outlet to the exterior, mechanical means for elevating grass along said inclined guides in series, said elevating means including spike-fitted frames moving with a circular orbital motion in relation to the respective inclined guides, the spikes of said frames extending through the apertures of said guides with an upward movement for elevating the grass, crankshafts operating said mechanical means, said crankshafts having their cranks set in opposite phase relation for the respective guides, means for delivering a hot gaseous drying medium to said one chamber, means for blowing

15 said medium from said one chamber to said other chamber, and passages for flow of said medium from said other chamber to beneath the respective guides for flow through the apertures therein and through the ascending grass thereon, the medium flowing through the grass on said second guide passing over said other chamber into said one chamber for mixing with the medium to be blown into said other chamber, and the medium flowing through the grass on the lower part of 20 said first guide escaping through said outlet.
